(57) **CLAIM**

The ornamental design for a safety razor handle, as shown and described.

DESCRIPTION

FIG. 1 is a top plan view of the safety razor handle, showing our new design;

FIG. 2 is a bottom plan view thereof;

FIG. 3 is a front elevation view thereof;

FIG. 4 is a right side elevation view thereof, the left side view being a mirror image;

FIG. 5 is a rear elevation view thereof; and,

FIG. 6 is a front isometric view thereof.

The SUPERMAX forming part of the claimed design is a registered trademark of Antonio Carlos Acatauassu Bittencourt and Yogesh Humbirrao Mohite.
